UNITED STATES PATENT OFFICE.

ALBERT T. QUANTZ, OF ROCK HILL, SOUTH CAROLINA.

METHOD OF WEAVING.

1,268,612.

Specification of Letters Patent. Patented June 4, 1918.

Application filed August 22, 1917. Serial No. 187,634.

To all whom it may concern:

Be it known that I, ALBERT T. QUANTZ, a citizen of the United States, residing at Rock Hill, York county, State of South Carolina, have invented certain new and useful Improvements in Methods of Weaving, of which the following is a specification.

This invention relates particularly to weaving cord fabrics and has for its object to provide a novel method whereby the fabric may be woven more economically than present methods allow, and which enables a better quality of fabric to be produced.

In the weaving of cord fabrics longitudinal stripes or ribs are formed therein by using warp threads of different thicknesses, the body of the warp being usually of single 10 ply thread and the ribs of double ply thread. Pattern forming devices, such as a stationary reed, or the drop bars, in looms where a drop bar stop motion is employed, arrange the warp threads in patterns just before the 20 warp enters the harness.

Due to the fact that the single ply warp threads wind sinuously over and under the woof threads while the thicker double ply warp threads, owing to their greater stiffness, do not, but lie substantially straight in the cloth, it would seem that in weaving a given length of cloth the single ply warp threads supplied should be materially longer than the double ply warp threads supplied, 30 in order that the ends would match and waste be avoided.

In practice the single ply warp threads have been sized and rendered comparatively non-elastic while the double ply threads have 40 been left in their original unsized and elastic condition, the single ply threads being wound upon a beam and the double ply threads being wound under considerable tension upon the same beam. The double ply threads are stretched in this winding-on process so that their length in their stretched condition is equal to the length of the non-elastic single ply threads.

In the process of weaving it is desired 50 that the "shortening" of the single ply threads due to their sinuous winding over and under the woof threads be approximately equal to the actual contraction of the double ply threads, resulting in the produc-

tion of a smooth cloth and no waste due to 55 the two kinds of thread running out at different times.

Heretofore two methods have been employed for supplying the different warp threads to the loom. In one method the 60 single ply sized threads and the double ply unsized threads have been wound in alternate layers on the same beam, the double ply threads being wound under tension, and both varieties passing over the same whip beam 65 when being run off into the loom.

Due, however, to the fact that the unsized threads must be wound upon the beam at equal intervals to secure uniform tension and that in weaving several of these threads are 70 brought together by the pattern forming devices to form each cord running through the fabric, the unsized threads, after leaving the beam, cross over numbers of the single ply threads in uniting to form a cord.

This method of letting off the warp threads has proved objectionable and impractical as the fibers projecting from the unsized thread warp around and entangle 75 with the sized threads in rubbing against 80 them and as a result the breakages, as the threads pass into the pattern forming devices, are excessive and the operation of the loom rendered unprofitable.

A second method has been to wind the 85 sized and unsized threads on separate beams and to mount the two beams on the back of the loom. This method has the advantage that the sized and unsized threads may be kept apart until they enter the pattern forming devices and thus avoids entanglement and breakage. It has major defects however, inasmuch as the weaver is greatly hindered by the presence of the additional beam, which renders difficult the tying up of 95 broken ends, the cloth produced is often uneven because of the tension on the unsized yarn being too great, and considerable waste is caused because of the practicable impossibility of getting both beams to run empty 100 at the same time. The necessity of having two beams and supports also renders this method more expensive than the single beam method.

This invention contemplates using a 105 method which has the advantages of both of the above described methods and the disadvantages of neither. The preferred form

of the apparatus used is shown in the accompanying drawings in which,

Figure 1 is a side view of a loom embodying my invention, part being broken away;

Fig. 2 is a perspective view of the same;

Fig. 3 is an enlarged view of portion of a whip roll; and

Fig. 4 is an enlarged view of a detail.

The frame of the loom is indicated by 10 in the drawings and the warp beam by 11, the usual brackets supporting the beam on the frame. The sized single ply warp threads 12 are shown being drawn from the beam and passing over a guide or whip roll 15 13 and then downwardly into the drop wires 14 of the stop motion devices which are adapted to stop the loom in the case of breakage of a warp thread. The unsized two-ply cords 15 pass from the beam over 20 the auxiliary guide bar 16 and thence into the drop wires 14. As shown in Fig. 1, the sized and the unsized threads are separated as they leave the beam and only come together again as they enter the drop wires, 25 after which they have little or no tendency to become entangled. From the drop wires the warp passes to the harness mechanism, indicated by 17, in the drawings, where the weaving is done.

30 The whip rolls or guides 13 and 16 are mounted upon brackets 18 and 19, respectively, secured to a rocking member 20 which comprises a portion of a device for compensating unevenness in the tension of 35 the warp, which, however, forms no part of this invention. The whip rolls or guides might be secured to the loom in other ways, provided they occupy positions which cause the warp threads to separate in the desired 40 manner.

Another feature of my invention is to 45 provide the guide 16 with a plurality of staggered holes 21 in the top adapted to receive the tight fitting stem portions of slotted members 22. The slots in the members 22 are sufficiently wide to permit the passage of a thread but will catch all large knots and lumps and break the threads causing the stop motion devices to drop and 50 stop the machine. The slotted members also

assist in forming the patterns by properly grouping the cords.

From the foregoing description it will be obvious that the disadvantages present in the methods of letting off hitherto employed in cord fabric looms have been avoided and that the improved method disclosed is more simple, inexpensive and efficient.

Having thus described the invention, what is claimed and desired to be secured by Letters Patent is:

1. The method of weaving fabrics of a single thickness having patterns therein formed by arranging and grouping different kinds of warp threads, which consists in winding substantially equal lengths of each kind of warp thread upon a single beam, drawing the threads simultaneously from the beam, separating the two kinds 70 as they leave the beam and maintaining them separated until they are grouped to form the pattern.

2. The method of weaving fabrics having patterns therein formed by arranging and grouping warp threads of different plies, which consists in sizing the warp threads having the least numbers of ply, winding substantially equal lengths of the sized and unsized threads upon a single beam, drawing the threads simultaneously from the beam, separating the different kinds as they leave the beam and maintaining them separated until they are grouped to form the pattern.

3. The method of weaving fabrics having patterns therein formed by arranging and grouping warp threads of at least two different plies the threads having the lesser plies being sized, which consists in winding substantially equal lengths of the sized and unsized threads upon a single beam, drawing the threads simultaneously from the beam, separating the different kinds as they leave the beam and maintaining them separated until they are grouped to form the pattern.

In testimony whereof I do affix my signature.

ALBERT T. QUANTZ.
